pediency in common use in sheet feeding devices. The gear 11 of the end feed roller of the series is in mesh with an idler or intermediate gear 24 journaled upon a stud shaft 25 mounted in the 5 end of a bracket plate 26 adjustably secured to the side frame 1 by means of a screw 27 engaged through an elongated slot 28 in the bracket plate 26. This provides for interchanging the gear 24 with a different diameter gear for a speed change 10 or variation.

The intermediate gear 24 is in mesh with a pinion 29 upon the end of a shaft 30 journaled in a journal bracket 31 adjustably secured and clamped to the side frame 1 by a screw 32 engaged 15 through an elongated slot in the side frame and screw-threaded in the journal bracket 31.

The shaft 30 at its opposite end has a miter pinion 33 fixed thereon in mesh with a miter pinion 34 fixed upon the end of a shaft or spindle 35 20 journaled in a bearing arm of the bracket 31 and held against longitudinal displacement by a collar or flange 36 on said shaft or spindle. The spindle has its upper end bored, split, and screw-threaded to provide a chuck for removably securing 25 a needle 37 thereon and clamped thereto by a collet 38 screw-threaded on the end of the shaft or spindle. The needle and its spindle are poised slightly at an angle and the point end of the needle extends upwardly into the rack slightly above the 30 plane of the base thereof pricking into several of the lowermost sheets of the stack as illustrated in Figures 2 and 4.

The needle is extremely tapered producing a long and very fine point which will readily penetrate the thickness of several sheets under the 35 load of the stack or weight imposed thereon, and its penetration is also aided by the rotation of the needle so that it will progressively prick through succeeding sheets in the descent of the stack 40 through the successive extraction of the sheets so that at least two of the lowermost sheets will be impaled. The lowermost sheet being in direct contact with the feed rollers, has a greater advancing pull imparted thereto than can be transmitted 45 to the next adjacent superposed sheet through the extracting sheet preventing its traverse with the lowermost sheet and the lowermost sheet being in direct contact with the rollers is

torn or pulled from the needle and discharged from the rack of magazine.

The needle in continuous rotation immediately casts off any loose lint or fibre administered under a tear or pull leaving no opportunity for the collection or accumulation of any quantity which would render the needle functionless or impair its utility. An oscillatory motion of the needle is regarded as the equivalent of the rotary herein particularly referred to, or any other action which will prevent a collection or deposit of lint or fibre on the point of the needle.

Having described my invention, I claim:

1. In a sheet feeding device for operating upon the lowermost sheet of a stack or pile for successively extracting the sheets individually, comprising, rotary sheet feeding means for frictional engagement with the lowermost sheet of the pile within a rack to advance and extract the lowermost sheet therefrom, a continuously rotating spindle removably carrying a needle, the needle tapering toward one end to provide an extremely fine point for penetrating several of the lower sheets at the rear end thereof for withholding against extraction, the sheets not directly operated upon by the sheet feeding means, a journal bracket journaled said spindle adjustable for changing the angle of the needle relative to the plane of the sheets, and gearing for transmitting said spindle journaled on said bracket as a unit therewith.

2. In a sheet feeding device for operating upon the lowermost sheet of a stack or pile for successively extracting the sheets individually, comprising, sheet feeding means for frictional engagement with the lowermost sheet of the pile within a rack to advance and extract the lowermost sheet therefrom, a continuously rotating spindle removably carrying a needle, the needle having its point penetrating several of the lower sheets at the rear end thereof for withholding against extraction, the sheets not directly operated upon by the sheet feeding means, a journal for said spindle, adjustable for changing the angle of said needle relative to the plane of the sheets penetrated by the point of the needle, and transmission means for rotating said spindle and needle.
